UNITED STATES PATENT OFFICE

OSCAR A. FLAGSTAD, OF MINNEAPOLIS, MINNESOTA, ASSIGNOR OF NINETY-FIVE PER CENT TO FOLDING CRATE AND BOX COMPANY, OF MINNEAPOLIS, MINNESOTA, A CORPORATION OF MINNESOTA

COLLAPSIBLE BOTTLE BOX

Application filed November 30, 1928. Serial No. 322,771.

This invention relates to collapsible carriers, and the primary object is to provide a foldable metal box that is particularly designed as a milk bottle carrier, and, as such, is provided with a number of novel, efficient and practical features by reason of which the box is especially adapted for the purposes noted. A further object is to provide a foldable metal box that is especially designed for use by milk delivery men, in which event it is desirable to have bottle containers that are strong and durable, that will stack neatly when filled or set up, and which may be folded up into compact units, when empty. Further and more specific objects will be disclosed in the course of the following specification, reference being had to the accompanying drawings, in which:

Fig. 1 is a perspective view of the box as set up ready for use.

Fig. 2 is a transverse sectional elevation of the box, set up.

Fig. 3 is a horizontal section on the line 3—3 in Fig. 2.

Fig. 4 is a sectional plan view similar to Fig. 3, but showing the box in a partly collapsed position.

Fig. 5 is a plan or top edge view of the box as seen when fully collapsed.

Fig. 6 is an enlarged detail perspective view showing the construction of certain portions of one of the wire frames.

Referring to the drawings more particularly and by reference characters, A and B designate opposite side sections of a crate or box having end sections C and D, and a two-part bottom section E, all of which sections are hingedly connected together, and foldable with respect to each other in a manner presently to be described.

The side sections A and B each consists of a substantially rectangular wire frame 7, the end or vertical lengths are connected by horizontal stay wires 8, and the bottom and top lengths of which are connected by verti-

cal stay wires 9. The ends of the wires 8 and 9 are preferably looped about the frame wires 7, and at their intersections they are preferably spot welded together, thus making each section, A and B, a rigid net work 50 of crossed and connected wires. The top run of each frame wire 7 is also provided with a pair of integrally formed, outwardly and upwardly offset tongues 10, which are so constructed and arranged that 55 they will snugly receive the bottom of a similar box and thus permit a rigid stacking of the boxes one upon the other.

The ends of the frames 7 serve as pintles for the end sections C and D, and at two diagonally opposed corners of the box these frame ends are offset inwardly, as at 11, so that when the box is collapsed, as in Fig. 5, there will be ample room between the sections A, C and D, B, to accommodate the 60 bottom section parts E and certain partitioning wires. It will also be noted that at the remaining or other diagonal corners of the box, the frames 7 are slightly offset outwardly, as at 12, (see Figs. 1, 3, 5 and 6), the 65 object of which also is to provide space for the partitioning wires by holding the end sections slightly out when the box is collapsed. Pivotedly secured to the frame of the section A is a small spring clip 13 that 70 is so arranged that it may be snapped over the frame B when the box is collapsed, so as to releasably retain it in that condition.

The end sections C and D are preferably formed of sheet metal, the vertical edges of 75 which are curled or turned about the vertical end bars of the side sections to form a hinge connection therewith. The bottom edges of the end sections are beaded, as at 14, to give 80 them rigidity. At its upper edge each end section is bent over a handle forming wire 85 15, as at 16, which handles also serve, like the elements 10, as stacking guides and holders.

A pair of spaced vertical rods or wires 17 90

are spot welded, or otherwise suitably secured, to the outer faces of the end sections C and D, and adjacent to parts of these wires the end sections are provided with 5 slots or openings 18 and 19. A pair of longitudinally disposed division or partitioning wires 20 have eyes at their ends which extend through the openings 18 to pivotally fasten to the wires 17, and a similar pair 10 of wires 21 spaced below the wires 20, are arranged to pivotally and slidably engage the wires 17 through the slots 19. The wires 20 are crossed by transversely extending wires 22 which rest thereon, and a center 15 wire 23, which is disposed under the wires 20. These wires 22 and 23 have eyes at their ends which pivotally engage the vertical wires 9 of the side sections A and B, and are prevented from dropping below their 20 predetermined horizontal positions, by the upper horizontal wires 8 of the side sections. The primary reason for offsetting the wires 22 and 23 with respect to each other, i. e., the first above and the latter below, the wires 25 20, is to provide clearance for the wires when the box is folded together. Similar transverse wires 24 and 25 cross the wires 21, two below and one above the latter, and complement the wires 22 and 23 to form transverse 30 partitions in the box. It will thus be seen that all the wires 20—25 cooperate to form chambers (twelve in the present instance) for the reception of the bottles. The bottom section comprises a pair of 35 rectangular sheet metal members 26 and 27 that respectively pivot to the lower bars of the side frames 7, and may be swung from the lower positions, as shown in Figs. 1-3, to the raised positions shown in Fig. 4. 40 When in their lower or horizontal positions these bottom members rest on a pair of transverse wires 28 having slotted loops at their ends for pivoting engagement with the side sections. This bottom, like the end sections, is preferably made of sheet metal and is provided with punched down dish portions 45 29 for receiving and positioning the lower ends of the bottles. These dish portions are also provided with perforations 30 for drain purposes.

When the box is to be folded together the bottom members 26 and 27 are first turned upwardly, and as this is done they will engage the cross wires 24 to move them upwardly together with the wires 21 and 25, as indicated by the dotted lines in Fig. 2. 55 The box can now be folded, through a parallelogram, as seen in Fig. 4, to the completely folded condition, indicated in Fig. 5, at 60 which time the spring clip 13 may be applied. To set up the crate it is only necessary to release the clip, expand the box to its rectangular position, and drop it upon the floor, whereupon the bottom members and 65 wires 21, 24, and 25 will drop into place.

It is understood that suitable modifications may be made in the general design and structural details of the invention as herein shown, provided, however, that said modifications come within the spirit and 70 scope of the appended claims.

Having now therefore fully shown and described my invention, what I claim to be new and desire to protect by Letters Patent is:

1. A collapsible box comprising hingedly 75 connected side and end sections foldable into adjacent parallel positions when the box is collapsed, bottom forming members hingedly secured for swinging movement up into the box before the sections are folded and partitioning members extending longitudinally and transversely within the box, certain of said partitioning members being slidably secured to the box and upwardly movable to permit said upward swinging movement 80 85 of the bottom forming members.

2. A collapsible box comprising hingedly connected sections and partitioning members dividing the box into vertical compartments, certain of said members being slidably connected to said sections to facilitate collapsing 90 of the box.

3. A collapsible box comprising hingedly connected sections and crossed partitioning members hingedly attached to certain of 95 said sections and dividing the box into vertical, substantially rectangular compartments.

4. A collapsible box comprising hingedly connected sections and crossed partitioning members dividing the box into vertical, substantially rectangular compartments, said partitioning members consisting of longitudinally and transversely extending wires 100 hingedly secured at their ends to the said box sections.

5. A collapsible box comprising hingedly connected sections and crossed partitioning members dividing the box into vertical, substantially rectangular compartments, said partitioning members consisting of longitudinally and transversely extending wires 110 secured at their ends to the said box sections, and some of which wires are vertically liftable to facilitate collapsing of the box.

6. A collapsible box having upwardly foldable bottom members, upper and lower sets of partitioning wires dividing the box into vertical compartments, the lower set of said partitioning wires being liftable to 120 permit the bottom members to be folded up.

7. A collapsible box having upwardly foldable bottom members, upper and lower sets of partitioning wires dividing the box into vertical compartments, the lower set of 125 said partitioning wires being liftable to permit the bottom members to be folded up, said bottom members having depressions registering with the bottom ends of the said compartments.

8. A collapsible box comprising wire frame side sections, sheet metal end sections, upwardly foldable sheet metal bottom members, and crossed wires secured at their ends to said sections to form partitions within the box, certain of said wires being liftable within predetermined limits to permit the upward folding of the bottom members.
9. A collapsible box comprising hingedly connected side and end sections, a pair of bottom forming members respectively hinged to the side sections for folding movement upwardly thereagainst, and cross members independent of the end sections and secured to the side sections intermediate their ends to serve as tie bars and for normally supporting the bottom forming members.
10. A collapsible box comprising hingedly connected side and end sections, a pair of bottom forming members respectively hinged to the side sections for folding movement upwardly thereagainst, and cross members secured to the side sections for normally supporting the bottom forming members, said side and end sections being respectively connected by wires forming partitions within the box.
11. A collapsible box comprising box forming sections hingedly connected by a pair of oppositely disposed rectangular wire frames, said frames being each reversely offset, at opposite ends, as and for the purpose described.
12. A collapsible box comprising box forming sections hingedly connected by a pair of oppositely disposed rectangular wire frames, said frames each being provided with outward and upwardly struck nesting members.
13. A collapsible box having wire frame side sections hingedly connecting the end sections, said frames being inwardly offset at two diagonally opposed corners of the box, and outwardly offset at the other two corners.
14. A collapsible box having wire frame side sections hingedly connecting the end sections, said frames being inwardly offset at two diagonally opposed corners of the box, and outwardly offset at the other two corners, said inward offsets being greater than the outward offsets.
15. A collapsible box comprising side and end sections hingedly connected at the four corners of the box, bottom forming members hinged to the side sections and foldable upwardly into the box, crossed partitioning wires pivotally secured at their ends to the sections and adapted to be contained between the side and end sections when the box is collapsed.
16. A collapsible box comprising side and end sections hingedly connected at the four
- corners of the box, bottom forming members hinged to the side sections and foldable upwardly into the box, crossed partitioning wires pivotally secured at their ends to the sections and adapted to be contained between the side and end sections when the box is collapsed, and means for releasably securing the various box parts together when the box is collapsed.
- In testimony whereof I affix my signature.
- OSCAR A. FLAGSTAD.
